CLAIM

I claim, the ornamental design for the brassiere with built-in cell phone pocket, as shown and described.

DESCRIPTION

FIG. 1 is a front elevational view of the brassiere with built-in cell phone pocket showing my new design;

FIG. 2 is a rear elevational view of the brassiere with built-in cell phone pocket thereof;

FIG. 3 is a left-side elevational view of the brassiere with built-in cell phone pocket thereof;

FIG. 4 is a top plan view of the brassiere with built-in cell phone pocket thereof; and,

FIG. 5 is a bottom plan view of the brassiere with built-in cell phone pocket thereof.
